DESIGN FOR AN EMBROIDERED TEXTILE FABRIC OR LIKE ARTICLE

Morris E. Darrish, St. Louis, Mo.

Application December 15, 1941, Serial No. 104,629

Term of patent 14 years

To all whom it may concern:

Be it known that I, Morris E. Darrish, a citizen of the United States, residing at the city of St. Louis, State of Missouri, have invented a new, original, and ornamental Design for an Embroidered Textile Fabric or Like Article, of which the following is a specification, reference being made to the accompanying drawings, forming a part thereof, in which Figure 1 is a plan view and Figure 2 is an enlarged fragmental plan view of an embroidered textile fabric or like article, embodying my new design.

I claim:

The ornamental design for an embroidered textile fabric or like article, substantially as shown.

MORRIS E. DARRISH.
